UNITED STATES PATENT OFFICE.

EDWARD C. TRUYTER, OF NEW YORK, N. Y., ASSIGNOR, BY MESNE ASSIGNMENTS, TO THE NORDLINGER-CHARLTON FIREWORKS COMPANY, OF SAME PLACE.

MANDREL FOR TUBE-MAKING MACHINES.

SPECIFICATION forming part of Letters Patent No. 634,191, dated October 3, 1899.

Application filed October 20, 1898. Serial No. 694,072. (No model.)

To all whom it may concern:

Be it known that I, EDWARD C. TRUYTER, a citizen of the United States, residing at New York, (Port Richmond,) Richmond county, 5 and State of New York, have made certain new and useful Improvements in Mandrels for Tube-Making Machines, of which the following is a specification.

My invention relates to the class of machines in which mandrels that have a slit to receive the end of a strip of paper are employed, whereby the strip is gripped and wound upon the mandrel as it rotates. In the paper-rolls produced by such mandrel as known to me the inner end of the strip is left projecting across the bore of the roll; and it is the object of my invention to cause the projecting end of the strip to be laid along the inner wall of the bore of the roll as the latter 20 is pulled from the mandrel.

To this end my invention consists in a mandrel having a bore and a slit in its side leading to said bore and adapted to receive the end of a paper strip and a tongue projecting 25 into said bore to lie in the path of the end of the strip as the roll that has been wound on the mandrel is pulled off from the same, said tongue acting to lay said projecting end of the rolled strip against the inner wall of the 30 bore of the roll.

The invention also consists in the novel details of improvement and the combination of parts that will be more fully hereinafter set forth and then pointed out in the claims.

Reference is to be had to the accompanying drawings, forming part hereof, wherein—

Figure 1 is a perspective view of a mandrel embodying my invention. Fig. 2 is a section on the line 2 2 in Fig. 1. Fig. 3 is a section 40 on the line 3 3 in Fig. 1. Fig. 4 is an end view of the mandrel, and Fig. 5 is an end view of a paper-roll before the inner projecting web is laid against the wall of the bore.

Similar numerals of reference indicate corresponding parts in the several views.

1 indicates a mandrel which may have screw threads 2 or other means at one end for attaching it to a rotative supporting and driv-

ing part. (Not shown.) The mandrel 1 has a bore 3, that opens at one end thereof, and 50 4 is a longitudinal slit in the mandrel which leads to said bore, the mandrel being preferably made from a tube. Near the outer end of the mandrel an opening 5 is made in the wall thereof at one side of the longitudinal slit 4 and communicating therewith, and 55 6 is a tongue formed in the wall of the mandrel between its end and the opening 5. The tongue 6 is preferably made by bending the corresponding part of the wall of the mandrel inwardly and by beveling the edge of the tongue from the part 7 toward the opening 5 along the edge 8. The tongue 6 is bent inwardly on a curve, as shown in Figs. 3 and 4, and its inner edge 9 preferably lies transversely of the bore 3, whereby the tongue extends into the bore of the mandrel.

When the mandrel is being used, the end of a strip of paper is passed through the slit 4, and then the mandrel is rotated. This 70 causes the end of the paper strip to be bent, as at 10 in Fig. 5, and as the mandrel continues to rotate the strip will be wound on the same in convolute form, producing a roll 11, having a web 10 extending across its bore, as 75 shown in the drawings. The roll 11 is next pulled from the mandrel, and in its passage along the same the web 10 will engage the tongue 6, and as it travels along the same the web 10 will be pressed by the tongue back 80 along the inner wall of the bore of the roll, whereby the bore will be clear and free. Paper-rolls thus produced are useful for fire-cracker bodies and other purposes.

Instead of making the tube or mandrel of 85 hollow metal it can be formed from a solid bar or built up in any desired way.

Having now described my invention, what I claim is—

1. A mandrel having a bore and a slit in its 90 wall leading to said bore, and a tongue projecting into said bore, substantially as described.

2. A mandrel having a bore and a slit in its 95 wall and also an opening in the wall at one side of said slit, and a tongue between said

opening and the end of the mandrel and projecting into said bore, substantially as described.

3. A mandrel having a bore and a slit in its 5 wall, and a tongue formed by bending the wall at one side of said slit inwardly so that it projects into said bore, substantially as described.

4. A mandrel having a bore and a slit in its 10 wall leading to said bore, and a tongue formed in the wall of the mandrel and having its edge beveled toward the inner wall of the bore, said tongue extending into the bore, substantially as described.

15 5. A mandrel having a bore and a slit in its

wall leading to said bore, and a tongue extending into said bore, the inner edge of said tongue extending transversely of the bore, substantially as described.

6. A mandrel having a bore and a slit in its 20 wall leading thereto, and a tongue bent on a curve and extending into said bore, substantially as described.

Signed at the city, county, and State of New York this 17th day of October, 1898.

EDWARD C. TRUYTER.
